Claims priority, application Brazil Aug. 12, 1960

4 Claims. (Cl. 239—337)

This invention concerns atomising discharge valves for containers of pressurised liquids and has for one object the provision of a new or improved valve of this character which is of a simple and inexpensive construction and may be made substantially entirely of plastic material.

Accordingly the valve of this invention comprises a cap having an aperture and a communicating bore therein, a discharge nozzle in said cap and in communication with said bore, a valve seat located in an axially fixed position within said bore of said cap and defining with the latter a chamber communicating with said discharge nozzle, such seat having a bore which emerges into said chamber and is adapted, in use of the valve, to be placed in communication with the liquid in the container, a resilient pad formed separately from the cap and mounted in the latter at the upper part of said chamber, a lever pivoted to said cap externally thereof, and a boss on said lever which passes through said aperture in said cap and bears on said pad, said lever being biased so that said boss normally applies pressure to said pad to distort the latter against the valve seat and close the bore therein, but capable of being pivoted against such biasing to release said pressure on said pad.

The valve of this invention, having a separate resilient pad to form the valve head, makes for an extremely simple manufacture and also improves the operation of the valve in that only a slight displacement of the lever is necessary to unseat the pad from the valve seat and thus release some of the contents of a container to which the valve is applied.

Advantageously, according to another feature of the invention, the lever is formed as an angle member having an upper arm disposed along the top of the cap and a side arm disposed along the side of the cap whereby pressure on the side arm of the lever towards the axis of the cap will cause the resilient pad to be unseated from the valve seat. By this means the valve is rendered easily manipulatable by a user and the entire assembly is given a compact form and attractive appearance.

In order that this invention may be understood more readily the following description is given, by way of example, of one embodiment of the invention with reference to the accompanying drawings, in which:

FIGURE 1 is a longitudinal section through the upper part of an aerosol producing liquid container incorporating a valve according to the invention; and

FIGURE 2 is a side elevation on a reduced scale of the upper part of the container and illustrating the operation of the valve.

As seen in FIGURE 1, the valve comprises a cap 1 sealed into the top of a container, which is conveniently a conventional cylindrical container as shown but may

2

be of any suitable desired shape, such cap including in its upper portion an aperture. On one side, the cap 1 is provided with a discharge passage 10 having a stamped metal atomising diaphragm 11 provided with a restricted orifice thus forming a discharge nozzle. On the other side of the cap and mounted between two supporting lugs is a pin 7 on which is pivoted an angled lever 5. The lever 5 is normally urged in a counter-clockwise sense as seen in FIGURE 1, by a coil compression spring 6, so that a boss 4 on the lower side of the upper arm of the lever is urged downwardly through the aperture in the upper portion of the cap.

The cap 1 is also provided with a bore into which is fitted a disc-shaped resilient pad 3. This pad is held in place against the underside of the upper portion of the cap 1 by raised shoulders at the top of a plug 2 which is tightly fitted into the bore in the cap. At its upper part the diameter of the plug 2 is reduced to form an annular chamber in communication with the passage 10 and from 20 the annular chamber fluid distributor ducts extend radially inwardly to a raised central valve seat slightly below the level of the said shoulders. Thus fluid can be fed from the valve seat to the discharge passage 10 whatever the orientation of the plug 2. The plug 2 has, at 25 its lower end, a downwardly extending central spigot having a central bore in which is fitted a dip tube 9 and a stamped metal diaphragm 12 having a central restricted orifice. To provide fluid communication between the 30 orifice of diaphragm 12 and the centre of the valve seat, the main portion of the plug 2 has a central bore of diameter d_1 having a restricted neck portion of diameter d_2 .

The action of the spring 6 on the lever 5 is to urge the 35 boss 4 downwardly onto the pad 3 and force the latter into fluid tight engagement on the valve seat.

Mounted between the two supporting lugs and just below pin 7 is a removable safety pin 8 which prevents 40 accidental pivoting of the lever 5 when the valve and container are not required for use. The side arm of the angled lever 5 is ribbed to facilitate pressing of the lever with the finger.

In order to open the valve the pin 8 is removed, pressure is exerted on the side arm of the lever 5, thereby 45 compressing the spring 6. Thus the boss 4 is raised and the resilient pad 3 is unseated from the seat at the top of plug 2 by the pressure of the pressurised liquid in the container. The liquid then passes through the radial ducts into the annular chamber through discharge passage 10 and emerges through the orifice of the atomising diaphragm 11 as a fine spray.

To close the valve, the side arm of the lever is released and the spring 6 urges the lever in a counter-clockwise direction, as seen in FIGURE 1, and the boss 4 passes the pad 3 back into sealing engagement with the valve seat.

The sizes of the orifices in diaphragms 11 and 12 and the values of d_1 and d_2 are chosen as functions of the physical properties of the liquid used.

We claim:

1. An atomising discharge valve comprising:

(a) a cap having a bore therein,

(b) a discharge nozzle projecting laterally outwardly from the side of said cap and communicating with the upper end of said bore in the cap,

- (c) a wall integral with said cap and forming the top of the latter,
- (d) said wall having an axial aperture therein,
- (e) a plug fitted fixedly in the lower end of said bore in the cap so as to be spaced below said top-forming wall of the cap,
- (f) said plug having a vertical central bore extending completely therethrough,
- (g) a valve seat on said plug at the upper end thereof and having a bore communicating with the bore in said plug,
- (h) a resilient valve member of disk-like configuration formed separately from said cap and plug and disposed between said top forming wall of the cap and the said valve seat,
- (i) said valve member being of greater dimensions than both the bore in the valve seat and said aperture in the top-forming wall of the cap and engaging said top-forming wall of the cap to close said aperture therein,
- (j) a lever pivoted to said cap externally thereof at a position remote from said valve member,
- (k) an end on said lever and
- (l) the lever being biased with said end normally projecting through the aperture in the top-forming wall of the cap and applying pressure to the valve member to press the valve member against the valve seat to close the bore therein, but being capable of being pivoted against such biasing to move said end out of contact with the valve member to release the pressure on the valve member.

2. A container for liquid under pressure, such container having mounted at the top thereof an atomising discharge valve comprising:

- (a) a cap having a bore thereon,
- (b) a discharge nozzle on said cap and in communication with said bore,
- (c) a wall integral with said cap and forming the top of the latter,
- (d) said top-forming wall of the cap having an aperture therein,
- (e) a plug fitted fixedly in the lower part of said bore in said cap,
- (f) said plug having a through bore which at one end enlarges into a recess,
- (g) a tube fitted into said recess and extending downwardly into said container,
- (h) a dished valve seat in said plug and a bore in said valve seat communicating with said through bore in said plug,
- (i) said seat defining with said cap a chamber communicating with said discharge nozzle,
- (j) a resilient valve member of disk-like configuration formed separately from said cap and plug and of dimensions greater than both the bore in the valve seat and the aperture in said top-forming wall of the cap,
- (k) said valve member being disposed in said chamber and closing the aperture in said wall,
- (l) a lever pivoted to said cap externally thereof at a position remote from said valve member,
- (m) an end on said lever and
- (n) the lever being biased so that said end normally projects through the aperture in the top-forming wall of the cap applying pressure to the valve member to press the valve member against said dished valve seat to close the bore therein, but being capable of being pivoted against such biasing to move said end out of contact with the valve member to release the pressure on the latter.

3. An atomising discharge valve comprising:

- (a) a cap having a vertical bore therein
- (b) an integral discharge nozzle projecting externally outwards from the side of said cap and communicating with said bore in the cap,

- 4
- (c) said nozzle having an apertured diaphragm for discharge therethrough of liquid in the form of a spray,
  - (d) a wall integral with the cap and forming the top of the latter,
  - (e) said top-forming wall of the cap having an axial aperture therein,
  - (f) a plug fitted fixedly in the lower end of said bore in said cap,
  - (g) said plug having a vertical through bore,
  - (h) an apertured diaphragm housed in the lower end of said bore,
  - (i) a dished valve seat formed on said plug and having a bore communicating with said vertical bore in said plug
  - (j) said valve seat defining with said cap a chamber communicating with said discharge nozzle,
  - (k) a resilient valve member of disk-like configuration formed separately from said plug and cap and having dimensions greater than both the bore in the valve seat and the aperture in said top-forming wall of the cap,
  - (l) said valve member being disposed within said chamber and closing said aperture in said wall,
  - (m) a lug projecting outwardly from the side of said cap opposite to said discharge nozzle,
  - (n) a lever pivoted to said lug at a position remote from said valve member,
  - (o) a boss integral with said lever and projecting through said aperture,
  - (p) said boss, valve member and valve seat being in alignment and
  - (q) the lever being biased so that said boss applies pressure to the valve member to press the valve member against the said dished valve seat to close the bore therein, but being capable of being pivoted against such biasing to move said end out of contact with said valve member to release the pressure on the latter.
4. A container for liquid under pressure, such container being of a generally cylindrical form and having its top defined by an atomising discharge valve comprising:
- (a) a cap having a vertical bore therein,
  - (b) an integral discharge nozzle projecting laterally outwardly from the side of the cap and communicating with said bore in said cap,
  - (c) said nozzle having an apertured diaphragm for discharge therethrough of liquid in the form of a spray,
  - (d) a wall integral with said cap and forming the top of the latter,
  - (e) said top forming wall of the cap having an axial aperture therein,
  - (f) a plug fitted fixedly in the lower end of said bore,
  - (g) said plug having a vertical bore extending completely therethrough,
  - (h) a recessed portion at the lower end of said plug communicating with said vertical central bore,
  - (i) a tube fitting into said recess and extending downwardly into said container,
  - (j) an apertured diaphragm housed in said recess and retained therein by said tube,
  - (k) a dished valve seat formed in said plug and having a bore communicating with said vertical bore in said plug,
  - (l) said valve seat defining with said cap a chamber communicating with said discharge nozzle,
  - (m) a resilient valve member of disk-like configuration formed separately from said plug and cap, and having dimensions greater than both the bore in the valve seat and the aperture in said top-forming wall of the cap,
  - (n) said valve member being disposed within said chamber and closing said aperture in said wall,

- (o) a lug projecting outwardly from the side of said cap opposite to said discharge nozzle,
- (p) a lever pivoted to said lug at a position remote from said valve member,
- (q) a boss integral with said lever and projecting through said aperture,
- (r) said boss, valve member and valve seat being in alignment and
- (s) the lever being biased so that said boss applies pressure to the valve member to press the valve member against the said dished valve seat to close the bore therein, but being capable of being pivoted against such biasing to move said end out of con-

tact with said valve member to release the pressure on the latter.
